UNITED STATES PATENT OFFICE.

JOHN A. S. GLANS, OF MINNEAPOLIS, MINNESOTA

PLANE.

No. 831,155.

Specification of Letters Patent.

Patented Sept. 18, 1906.

Application filed May 20, 1905. Serial No. 261,313.

To all whom it may concern:

Be it known that I, JOHN A. S. GLANS, of Minneapolis, Hennepin county, Minnesota, have invented certain new and useful Improvements in Planes, of which the following is a specification.

My invention relates to carpenters' planes; and the object of the invention is to improve and simplify the mechanism for locking the bit in the stock and adjusting it lengthwise and laterally therein.

A further object is to provide a plane which is capable of easy and quick adjustment and is composed of comparatively few parts.

The invention consists generally in an improved means for locking the bit and adjusting its cutting edge toward or from the mouth of the stock.

Further, the invention consists in improved means for oscillating the bit to align its cutting edge with the sole of the stock.

Further, the invention consists in providing an adjustable handle, and, further, the invention consists in various constructions and combinations, all as hereinafter described, and particularly pointed out in the claims.

In the accompanying drawings, forming part of this specification, Figure 1 is a longitudinal vertical section of a plane embodying my invention. Fig. 2 is a side elevation looking toward the opposite side of the plane, a portion of the stock being broken away to illustrate the device for locking the bit therein. Fig. 3 is a sectional view on the line $z-z$ of Fig. 2. Fig. 4 is a similar view with the bit and break-iron or blade removed. Fig. 5 is a detail view illustrating the locking device in its unlocked position. Fig. 6 is a similar view showing the locking device in its locked position. Fig. 7 is a detail sectional view illustrating the position of the locking device beneath the bit and indicating in dotted lines the unlocked position of the lever. Fig. 8 is a detail view of the device for rocking or oscillating the bit on the bed of the stock to align its cutting edge with the sole of the stock.

In the drawings, 2 represents the stock of the plane. I have shown my invention applied to a smoothing-plane; but it will be understood that it is applicable to any other type. The stock is provided with the usual mouth 3, nose 4, and with a handle 5, that is

adjustable at its lower end on the stock by means of a slot 6 and set-screw 7.

8 represents the inclined bed of the stock whereon a sleeve 9 is adjustable by means of a tongue 10, having a slot 11 and a set-screw 12, which passes through said slot into said bed. By loosening said screw the sleeve can be moved up and down from or toward the mouth of the stock. Within said sleeve a pin 13 is arranged to fit snugly and has a partial revolution therein and is provided with an operating-lever 14, which projects through a slot 15 in said sleeve. The upper end of the pin 13 is provided with a head 16, eccentrically mounted on the end of the pin and elongated in form and adapted to project through a correspondingly-shaped slot 17 in the bit and in the break-iron. One end of the slot 15 is provided with an upwardly-turned extension 18, which causes the pin to slide upwardly in the sleeve and raise the head 16 above its normal position, and when the lever 14 is moved into the end 18 of the slot 15 the head 16 will be turned, so that it will coincide with the slot in the bit and break-iron and allow them to be removed from the plane. When the handle 14 is turned toward the middle of the slot 15, the pin 13 will be drawn down and the head 16 turned at right angles to the slot in the bit and break-iron and bearing on the break-iron will draw it and the bit down firmly upon the bed of the plane and hold them securely in that position. The head being eccentrically mounted on the pin, it follows that whenever the lever 14 is moved to one side or the other of the middle of the slot 15 the bit and break-iron will be moved lengthwise to project or retract the cutting edge of the bit. In this way the person using the tool can very easily and quickly adjust the bit with respect to the sole of the stock to adapt it for the wood that is being planed. Whenever desired, the operator can throw the lever 14 into the end 18 of the slot and release the clamp on the bit and allow its removal, if desired, from the plane. The bit and break-iron are preferably secured together by means of the thumb-screw 19.

It is desirable in a device of this kind to provide some means for alining the cutting edge of the bit with respect to the sole of the plane, either raising or lowering one corner to compensate for any slight irregularity that may be produced in the cutting edge through

the operation of sharpening it. I therefore provide a rectangular slot 20 in the bit and a bearing 21 on the upper edge of the handle 5 for a pin 22, that fits within the slot 20 and has its ends arranged to bear on the sides of the slot. The bearing 21 has a cam-slot 23 formed therein, and a lever 24 mounted on the pin 22 projects through said slot and bears on the sides of the same. When, therefore, this lever is moved in said slot, the pin 22 will be given a slight lengthwise movement to impart an oscillating or rocking movement to the bit. A very slight movement of the lever 24 will be sufficient to oscillate the bit and aline its cutting edge with respect to the sole of the plane.

I claim as my invention—

1. The combination, with a plane-stock provided with a bed, of a sleeve having a tongue adjustably secured on said bed, a pin fitting within said sleeve and provided on one end with an eccentrically-mounted head, a bit having a slot to receive said head, and means for imparting a rotary and lengthwise movement to said pin.

2. The combination with a plane-stock, of a bit mounted thereon and having a transverse slot, a pin arranged beneath said bit and having a head eccentrically mounted on one end thereof and arranged to project through the slot in said bit and move it lengthwise when said pin is rotated and lap the edges of said slot and lock said bit on said stock when turned crosswise of said slot, and means for rotating said pin and moving the same lengthwise to release said bit, substantially as described.

3. The combination with a plane-stock, of a bit mounted thereon and having a transverse slot, a pin supported beneath said bit and having an eccentrically-mounted T-shaped head on one end to project through said slot and be turned crosswise thereof to lock said bit, and means for rotating said pin to move said bit lengthwise and to move said

pin lengthwise to release or clamp said bit, substantially as described.

4. The combination with a plane-stock, of a bit mounted thereon and having a transverse slot, a sleeve mounted on said stock beneath said bit and at right angles substantially to the plane of said bit, and said sleeve having a transverse slot, a pin fitting snugly within said sleeve and having an operating-lever projecting through the transverse slot therein, and an eccentrically-mounted head provided on the upper end of said pin and adapted to pass through the slot in said bit whereby when said lever is moved to rotate said pin said bit will be moved lengthwise, substantially as described.

5. The combination with a plane-stock, of a bit mounted thereon and provided with a transverse slot, a sleeve provided beneath said bit at right angles substantially to the plane thereof and having a transverse slot 15 provided with an upwardly-turned extension at one end, a pin fitting within said sleeve and having an operating-lever projecting through said slot and adapted to slip into said extension and allow upward movement of said pin, and an eccentrically-mounted head provided on the end of said pin and projecting through the slot in said bit to lap the edges of said slot when the pin is rotated, substantially as described.

6. The combination with a plane-stock provided with a bed, of a sleeve having a tongue adjustably secured on said bed, a bit having a slot, and a pin fitting within said sleeve and having an eccentrically-mounted head to enter said slot, substantially as described.

In witness whereof I have hereunto set my hand this 15th day of May, 1905.

JOHN A. S. GLANS.
